UNITED STATES PATENT OFFICE

FRANK BRADY, OF DENVER, COLORADO

TRICK POCKETBOOK

Application filed October 23, 1928. Serial No. 314,368.

This invention relates to a trick pocket book or trick wallet.

The object of the invention is the construction of a pocket book or wallet, which will cause considerable amusement or entertainment for the person who solves the problem of opening the same.

Another object of the invention is the construction of a simple trick or "puzzle" pocket book, which is comparatively inexpensive to manufacture, and by reason of the entertainment derived when opening the same will be an excellent advertisement novelty for business men to use in exploiting or selling their goods, since a suitable ad. can be exposed upon the pocket book.

With the foregoing and other objects in view, my invention comprises certain novel constructions, combinations and arrangements of parts as will be hereinafter fully described, illustrated in the accompanying drawings, and more particularly pointed out in the appended claims.

In the drawings:

Figure 1 is a view in front elevation of a device constructed in accordance with the present invention.

Figure 2 is a sectional view taken on line 2-2, Figure 1, and looking in the direction of the arrows.

Figure 3 is a view in rear elevation of my device.

Figure 4 is a view showing the manner of opening the pocket book.

Figure 5 is a view in elevation of the back of the device.

Figure 6 is a view in elevation of the disc-like shield.

Referring to the drawings by numerals, 1 designates the back and 2 is the front. The front 2 is provided in its upper portion with edge ribs 3 and 4 and intermediate parallel ribs 5. The front 2 is sewed, by stitching 6, to the back 1.

The shield 7, which is preferably shown as a disc, is sewed to the back 1 by a line of stitches or "loops" 8; these loops or stitches do not go through the ribs 3, 4 and 5 because the ribs slide between back 1 and shield 7.

Further, the line of stitching or loops 8 do

not cover or include the laterally movably edge ribs 3 and 4 (see Figs. 1 and 4). The ends of the stitching 6 terminate short of transverse line upon which stitching or loops 8 are formed, so that in solving the puzzle, either edge rib 3 can be pulled outwardly, as shown in Figure 4, and this pulling or moving of rib 3 outwardly, gives a free space, at 9, for the operator's finger to get at the edge of the next or intermediate rib 5, and by pulling outwardly and downwardly on the intermediate ribs, they will sag sufficiently to spread them apart, allowing the contents of the pocket, formed by the front and back, to be exposed to the operator.

In Figure 1, the pocket book appears as it is presented to a person for solving the puzzle. It will be noted that the "guard" shield 7 covers the inner end of the ribs 3, 4 and 5, with all the ribs straight and parallel. Hence the operator is mystified as to how to get into or open the pocket book, notwithstanding that it is very easy to raise the lower end of the shield, then move either one of the edge ribs to one side and thereby leave the lower or inner ends of the intermediate ribs readily accessible to be pulled upon to open the pocket book below the line of stitching or loops 8 as clearly indicated in Figure 4.

Therefore, it will be seen that my pocket book is mystifying to an ordinary observer; that it is very inexpensive in construction owing to its few parts, and yet it is durable and can be operated a number of times, which is advantageous owing to the great amount of pleasure afforded thereby.

It is to be understood that the stitching or loops 8 pass between the ribs and through the back and shield, with the ribs sliding therebetween.

While I have described the preferred embodiment of my invention and illustrated the same in the accompanying drawings, certain minor changes and alterations may appear to one skilled in the art to which this invention relates, and I therefore reserve the right to make such changes or alterations as shall fairly fall within the scope of the appended claims.

What I claim is:

1. In a device of the class described, the combination of a back, a front against said back, said front provided with edge ribs and intermediate ribs, a shield against said front and covering some parts of all of the ribs, and stitching part way across the shield, between and across said intermediate ribs and not including the edge ribs for permitting lateral movement of said edge ribs.
- 10 2. In a device of the class described, the combination of a back, a front against said back, said front provided with laterally movable and slidably edge ribs, said front also provided with intermediate ribs between said edge ribs, a shield against all of said ribs, fastening means between the ribs and extending across all but said edge ribs and connecting the shield and back together and allowing said intermediate ribs to have a sliding movement between the shield and back, and said edge ribs normally parallel with the intermediate ribs under said shield, but adapted to be moved laterally to give access to the inner ends of the intermediate ribs, substantially as shown and described.
- 15 3. In a device of the class described, the combination of a back, a front against said back, a shield against said front, said front provided with ribs behind said shield, a line of stitching partly across said shield and extending between the ribs and leaving the outer ribs free for lateral movement, and a second line of stitching holding the front and back together around parts of their edges but terminating short of said first mentioned line of stitching leaving said outer ribs free for lateral movement.

In testimony whereof I hereunto affix my signature.

FRANK BRADY.
